JOSEPH K. NYCE AND IRWIN C. HUNICKER, OF SKIPPACK, PENNSYLVANIA,
ASSIGNORS TO THEMSELVES, WILLIAM D. HEEBNER, DAVID D. NYCE,
AND ISAIAH A. ANDEN, ALL OF SAME PLACE.

CAR-COUPING.

SPECIFICATION forming part of Letters Patent No. 289,357, dated November 27, 1883.

Application filed July 6, 1883. (No model.)

To all whom it may concern:

Be it known that we, JOSEPH K. NYCE and IRWIN C. HUNICKER, both of Skippack, in the county of Montgomery and State of Pennsylvania, have invented a new and Improved 5 Car-Coupler, of which the following is a full, clear, and exact description.

The invention consists in a draw-head provided with longitudinal slots in the sides and 10 bottom, in which side slots a cross-bar slides, which has a bottom-guide projection passing into the bottom slot. The ends of the cross-piece project from the sides of the draw-head and are adapted to strike against the lower 15 ends of bail-shaped frames pivoted on the draw-head, and to throw the said frames over hooks on the outer ends of the opposite draw-heads, thereby coupling them.

Reference is to be had to the accompanying 20 drawings, forming part of this specification, in which similar letters of reference indicate corresponding parts in all the figures.

Figure 1 shows two of our improved car-couplers in longitudinal elevation, parts being 25 broken out and others shown in section. Fig. 2 is a plan view of the same, parts being broken out and others shown in section. Fig. 3 is a perspective view of the slide in the draw-head.

30 The draw-head A is provided on its upper surface and at its outer end with an upwardly and slightly backwardly projecting hook or boss, B, which is slightly undercut on its rear edge. A bail-shaped or inverted U-shaped frame, C, is mounted to swing on the projecting ends of a transverse rod or shaft, D, in the draw-head, the shanks of the frame C being each provided a short distance from their free ends with an eye, E, through which the 35 rod or shaft D is passed. The ends C' of the shanks of the frame C thus project beyond the shaft or rod D. The draw-head A is provided with a longitudinal slot, F, in each side, and with a central longitudinal slot, G, in the 40 bottom. A cross-piece, H, slides in the slots F, which cross-piece is of such length that its ends project beyond the sides of the draw- 45

head, and on its under side the cross-piece is provided with a guide-block, J, which slides in the guide-slot G in the bottom of the draw-head. To the front edge of the cross-piece a plate, K, is fastened, which extends in the direction toward the outer end of the draw-head, and which can slide on the bottom of the draw-head. 50

The operation is as follows: The coupling-frames C are thrown up, as shown, in the left-hand draw-head of Fig. 1, and the ends C' of the same will then push the cross-piece H forward until it rests against the front ends of the slots F. The plate K will project from the front end of the draw-head. If then the draw-heads come together the plates K will be forced inward very suddenly, and will press the ends C' of the frame C toward the 65 inner end of draw-head very rapidly, and will swing the bail-shaped frame C of one draw-head over the coupling hook or boss B of the other draw-head. The cars are thus coupled automatically. The cars can be uncoupled by simply raising the frames C. 70

We do not abandon or dedicate to the public any patentable feature set forth herein and not hereinafter claimed; but reserve the right to claim the same either in a reissue of any 75 patent that may be granted upon this application or in other applications for Letters Patent that we may make.

Having thus described our invention, what we claim as new, and desire to secure by Letters Patent, is— 80

1. In a car-coupling, the combination, with the draw-head having the horn or hook B, and the sliding plate K, provided with the single cross-piece H, with its ends projecting through slots in the draw-head, and beyond the sides of the latter, of the bail or frame C pivoted to the sides of the draw-head and having ends C' projecting beyond its pivot and adapted to be acted upon by the ends of the 85 cross-piece H, as shown and described, and for the purpose set forth.

2. The combination, with the draw-head A, having a projection, B, and provided with side

slots, F, and a bottom slot, G, of the cross-piece H, projecting through the slots F and from the sides of the draw-head, the bottom-guide projection, J, on the cross-piece, the plate K secured to the cross-piece, and of the bail-shaped frame pivoted to the sides of the draw-head, and having its ends C extending beyond its pivotal point and acted upon by the

ends of the cross-piece H, substantially as herein shown and described.

JOSEPH K. NYCE.
IRWIN C. HUNICKER.
